RAILING PANEL

James J. O'Donaughy, 5295 Boundry Road, and James Stewart, 5075 Boundry Road, both of Vancouver, British Columbia, Canada

Filed Oct. 24, 1960, Ser. No. 62,602

Term of patent 14 years

(Cl. D54—2)

The FIGURE is a perspective view of a railing panel, showing our new design.

The dominant features of our design reside in the portions shown in full lines on the drawing.

We claim:

The ornamental design for a railing panel, as shown and described.
